Des. 196,514
Patented Oct. 8, 1963

196,514

CASING FOR A MINIATURE TAPE RECORDER OR SIMILAR ARTICLE

Viktor Stuzzi, Vienna, Austria, assignor to
Paul E. King, New York, N.Y.

Filed Oct. 31, 1961, Ser. No. 67,322

Term of patent 14 years

(Cl. D26—14)

Fig. 1

Fig. 2

FIG. 1 is a front perspective view of a casing for a miniature tape recorder or similar article, showing my new design; and

FIG. 2 is a rear perspective view thereof.

I claim:

The ornamental design for a casing for a miniature tape recorder or similar article, substantially as shown.
